UNITED STATES PATENT OFFICE.

HENRY JACKSON DAVIS, OF BIRMINGHAM, ALABAMA, ASSIGNOR OF THREE-FOURTHS TO HARRY WELLS COFFIN, SAMUEL T. ECHOLS, AND GEORGE ROBERT EARLY, OF SAME PLACE.

ROTARY ENGINE.

SPECIFICATION forming part of Letters Patent No. 538,821, dated May 7, 1895.

Application filed July 26, 1894. Serial No. 518,655. (No model.)

To all whom it may concern:

Be it known that I, HENRY JACKSON DAVIS, a citizen of the United States, residing at Birmingham, in the county of Jefferson and State of Alabama, have invented certain new and useful Improvements in Rotary Engines; and I do hereby declare the following to be a full, clear, and exact description of the invention, such as will enable others skilled in the art to

10 to which it appertains to make and use the same.

My invention relates to that class of steam engines in which a piston revolves within a cylinder in a rotary direction; and the objects of my improvement are, first, to provide an 15 engine of that class of a simple and cheap construction having a circular cylinder with a circular piston head attached by a plate to the main shaft the piston head rotating within the cylinder formed in the casings; second, to construct a rotary engine having a vertical steam valve, and vertical cut off valve inclosed in a steam chest, the valves extending downward 20 into the cylinder when the port is open for the admission of steam, the valves when raised by 25 the rotation of the piston head shutting the steam off from the cylinder; third, to provide a rotary engine having an endless circular cylinder in which a circular piston head rotates the head provided with packing rings to make it 30 steam tight, the steam operating against the head of the piston. I attain these objects by the mechanism illustrated in the accompanying drawings, in which—

Figure 1 is a vertical sectional view of my 35 engine through the center. Fig. 2 is a vertical cross-sectional view of the same through the center. Fig. 3 is a vertical cross-sectional view of the steam valve through the center. Fig. 4 is a vertical cross-sectional view of the 40 cut-off valve through the center.

Similar letters refer to similar parts throughout the several views.

The casings A. A are made of cast iron or other suitable metallic material. The casings 45 are provided with the usual flanges on the outer edge and are secured together by bolts through the flanges in the usual manner. At the lower edge the casings are provided with flanges turned at a right angle, to form a base 50 on which the engine stands.

The inside of each casing is provided with a semi-circular recess B. The recesses are turned and finished to form a circular cylinder when both cases are bolted together, a space being reserved for a circular plate to 55 revolve between the casings, as hereinafter described. The cylinder is provided with an exhaust port R placed at any desired position.

A main shaft C is journaled in suitable 60 bearings formed in the casings. The shaft extends through the casings on both sides, and the usual stuffing boxes having glands D. D are formed on the outer ends of the shaft bearings, to secure a steam tight joint surround- 65 ing the shaft.

A circular plate E is secured on the center of the main shaft by any of the usual methods. On the periphery of the plate, a piston head F is secured as shown, or in any other desirable manner attached to the plate. The piston head body is formed circular and with a curve to fit the cylinder formed in the casings. The head is provided with spring packing rings G fitted in recesses formed in the head in the 75 usual manner. The back part of the head is formed tapering the taper ending even with the periphery of the circular plate to which the head is attached.

The casings on both sides near the recesses 80 forming the cylinder are provided with the usual form of spring packing rings H. H to form a steam tight joint, between the casings and the piston head plate.

On the head of the casings an extension for 85 a steam chest is formed, through which the steam is admitted to the cylinder, a steam pipe I being attached to the steam chest as shown. A passage or port J leading from the steam pipe extends across the steam chest 90 and turns downward opening into the cylinder. The top of the steam chest is inclosed by a cover Q the cover secured with stud bolts in the usual manner.

A circular plunger valve K having an ap- 95erture L through it to admit steam is fitted in a circular chamber formed in the steam chest. The said valve when down with the point resting on the piston head plate, admits steam through the port, and when raised by the 100

piston head, as shown by dotted lines, the valve closes the steam passage.

A flat cut off valve M having an aperture N through it to admit steam is fitted in grooves formed in the steam chest. The said valve when down forms a wall across the cylinder, to force the steam when admitted to follow the piston head. The valve when raised cuts the steam off from the admission port, preventing the steam from entering the cylinder until the valve is lowered to form the wall, when steam is again admitted to the cylinder as before described.

On the head of the valve K is fitted a bar O. The bar is attached to the valve head by any suitable means. The bar extends through an aperture P formed in the steam chest, the end of the bar resting on the head of the cut off valve M as shown. When the engine is in operation, the rotation of the piston head, will first raise the valve K, and afterward raise the valve M. The rotation of the head would first release the valve K and allow it to drop, but it not being desirable to turn steam on until the cut off valve is lowered to place, the cut off valve holds the steam valve up by the bar O resting on its head, and the cut off valve M descending first forms the cylinder wall before steam is admitted to the cylinder.

Having thus described my invention, what I claim as new, and desire to secure by Letters Patent, is—

1. In a rotary engine, the combination of the outer casings having a semicircular recess formed in each casing the recesses forming a circular cylinder when the casings are bolted together the head of the casings forming a steam chest, an exhaust port opening from the cylinder, an inlet steam port opening to the steam chest the steam port extending across the steam chest and opening downward to the

cylinder, a main shaft journaled in the casings the shaft provided with a circular plate mounted thereon, a piston head attached to the periphery of the plate the piston head provided with rings to make a contact with the walls of the cylinder the head formed with a convex taper extending back from the rings, a steam valve operating in a chamber formed in the steam chest the valve extending downward in the cylinder and formed convex on the end to make a close contact therein, a cut off valve operating in grooves formed in the steam chest the valve extending downward in the cylinder and formed convex on the end to make a close contact therein, both valves having openings to coincide with the steam port the valves operated by the rotation of the piston head, substantially as and for the purpose set forth.

2. In a rotary engine, the combination of the casings secured together forming a circular cylinder, a main shaft journaled in the casings having a piston head secured thereon, a steam chest formed on the head of the casings having a steam valve, and cut off valve operating therein, a bar secured on the head of the steam valve the bar extending through an aperture formed in the steam chest, the end of the bar resting on the head of the cut off valve when both valves are up, the bar preventing the descent of the steam valve until after the descent of the cut off valve, substantially as and for the purpose described.

In testimony whereof I affix my signature in presence of two witnesses.

HENRY JACKSON DAVIS.
